UNITED STATES PATENT OFFICE.

CHARLES S. HENSHAW, OF BOSTON, MASSACHUSETTS.

ADVERTISING DEVICE.

1,414,017.

Specification of Letters Patent. Patented Apr. 25, 1922.

Application filed August 21, 1920. Serial No. 405,112.

To all whom it may concern:

Be it known that I, CHARLES S. HENSHAW, a citizen of the United States of America, and a resident of Boston, in the county of Suffolk and Commonwealth of Massachusetts, have invented certain new and useful Improvements in Advertising Devices, of which the following is a specification.

This invention relates to advertising devices wherein it is desirable to simulate the issuance of smoke or steam therefrom to thereby give a more realistic appearance to the device and at the same time attract wide attention thereto. The present invention is 10 herein shown in connection with a mammoth cigar which in practice will have the appearance of the genuine article, though much larger, which has been lighted and is still burning, smoke arising apparently from the lighted end, mystifying the looker-on as to its source, and generally attracting greater attention than if the smoke were not in evidence.

It is an object of this invention to produce 25 an advertising device that represents an article such, for instance, as a cigar, that is desired to be forced upon the attention of the public, and preferably it should be of such construction and arrangement as to 30 permit of transportation in a prominent position upon a suitable vehicle.

It is also an object of this invention to so construct and arrange the device that it may remain in a given or fixed position either in 35 suspension or resting upon a suitable support and emit improvised smoke or steam as the case may be.

The invention further consists in certain 40 novel features of construction and arrangement of parts which will be fully understood by reference to the description of the drawings and to the claims hereinafter given.

Of the drawings:

Figure 1 represents an elevation of a 45 lighted cigar which happens to be a convenient article of trade with which the present invention may be used.

Figure 2 represents a vertical longitudinal 50 section of Figure 1.

Figure 3 is a detail in elevation of the removable combined charge holder and smoke chamber.

Figure 4 is a right hand end view of Figure 55 3.

Figure 5 is an enlarged section on the line 5—5, Figure 1.

Similar characters designate like parts throughout the several figures of the drawing.

Referring to the drawings, 10 is a shell made of any suitable material and in this instance shaped and suitably painted to represent a lighted cigar with the ashes thereon. Air inlet and smoke outlet holes 11 and 12 respectively are provided at opposite ends of said shell 10 for a purpose to be explained. Removably mounted in the shell at the right hand end thereof is a combined charge holder and smoke chamber 13 cylindrical in shape, which is divided into communicating chambers as 14, 15, 16, 17 and 18, said chambers being separated by wire or perforated partitions 19, an opening 20 being provided in said cylinder 13 to afford a ready means of replenishing the charge in the chambers as required. The chamber 18 which will be hereinafter called the smoke chamber, is provided with perforations 21, preferably of such size and number as to agree with the holes 12 of the shell 10 and will in practice register therewith. The cylinder 13 is provided with longitudinal cleats 22 fast therewith which are adapted to be guided in ways 23 provided in the shell, said cleats acting to prevent rotary movement of the said shell and insuring the proper registration of the holes 12 and 21. At its right hand end the cylinder 13 is provided with a handle 24 which in practice will be concealed in a pocket 25 by the cover 26. It is obvious that upon removal of the cover 26 the handle may be grasped to withdraw the cylinder 13 from the shell.

Located inside the shell 10 and to the left of cylinder 13 is an electric fan 27, the purpose of which will be hereinafter explained.

The charge so called, previously referred to, in this instance consists of pumice or similar porous material capable of absorbing 100 quantities of hydrochloric or muriatic acid, which is highly volatile, and shown in chamber 14, while in chamber 16 a quantity of ammonium carbonate is placed which is also highly volatile.

The fumes arising from each of these chambers together with a draft of air intermingling therewith will instantly cause the formation of a gas that to all intents and purposes resembles smoke or steam.

When the device is to be mounted on a vehicle, for advertising purposes and transported thereby, it will be placed preferably longitudinally of the vehicle with the pointed end forward so that during its travel a draft of air will be forced through the holes 11 which will pass through the several screen partitions 19 but first contacting with the acid laden material in chamber 14 and thereafter with the ammonium carbonate in chamber 17 whereby fumes from both chambers will become intermixed.

The smoke thus formed and constantly accumulating will be forced into the smoke chamber 18 from which it finds gradual exit through the holes 21 of the cylinder 13 and 12 of the shell 10. The chamber 18 acts as a reservoir for the storage of gas which is bound to accumulate and which cannot escape through the holes 21-12 as fast as generated while the device is in motion, so that a considerable volume of gas will be held in reserve which will continue to escape through the said holes for a considerable time after the device has stopped its movement through the air or after further generation of the gas has practically ceased, which would occur when the current of air no longer circulated through the shell 10.

In practice it has been found advisable to use a retarding means to curb the too ready formation and exit of the smoke from the cylinder 13 and for this purpose a simple means has been devised. In chambers 15 and 17 fibrous material such as excelsior, curled hair, cotton batting or similar material is packed in such manner as to permit a current of air and gas to pass therethrough but which is necessarily retarded thereby in its passage. It has been found by experiment that when the device is in motion or traveling through the air an appreciable air pressure is formed in the shell and it was also found to be advisable to retard the rush of air on its way to the smoke chamber, as by so doing a smoky gas of less density of volume finally resulted and it also added longer life to the gas generating mediums. The amount of acid and ammonium carbonate to be used will depend upon the purpose and the volume of improvised smoke or steam required.

So, too, the amount and solidity of packing of the fibrous material will be governed by the flow or volume of smoke or steam desired. It will be noted that the cylinder 13 does not tightly fit into the shell 10, a space 28 being left between the two which in this instance serves as a sort of relief passage which allows a current of air to mingle with the smoke prior to its exit through the holes 12. This is not a necessary or vital feature of the invention, as it is obvious that the said cylinder might properly be snugly fitted to the shell, and the volume of smoke

issuing therefrom would be graduated by the quantity of acid and ammonium carbonate used, and the pressure of air passing through the chambers as well as the density of the fibrous material used as a retarding means for the passage of said air and gas mixture. When it is desired to mount this device in a stationary position either by suspending it from above or at rest upon a suitable support, it will be necessary to artificially create a draft of air to pass through the device for the purpose above explained, and to that end a fan 27 is herein shown which will be preferably electrically driven and so arranged as to tend to create a vacuum in the shell 10 and thereby cause a draft of air to enter the holes 11 and be forced through the several chambers finally issuing through the holes 12 in a smoke or steam like gas. The fan 27 which is in the electric circuit 28 may be controlled by means of a suitable switch as indicated at 29.

It will be understood that to further mystify the on-looker, the supports or suspension means for this device should be as simple and light as the device will permit so that the impression may not be gained that the smoke or steam is lead thereto from an outside source.

While this invention has been shown and explained in connection with an advertising device, it is obvious that it may be used for other purposes as, for instance, in connection with an air whistle such as is necessary on motor boats. It will be readily seen that a container similar to cylinder 13 might be interposed between the whistle and the source of air supply therefor, which would generate a smoky gas, and upon opening the whistle valve the gas will perform its intended function of operating the whistle and would also indicate to those at a distance that the whistle on that particular boat had been blown, each blast accompanied by a volume of smoke. It sometimes happens that the blast of a steam whistle is not heard by those for whom it was intended and yet the puff or series of puffs of steam issuing therefrom will convey the message equally well to a trained navigator or pilot.

It is not intended to limit this invention strictly to advertising devices of whatever shape or description, nor is it the intention to limit it to the precise smoke producing ingredients used as it is obvious that other compounds may be used that give the results aimed at in this invention.

Having thus described my invention what I claim is:

1. In an illusionary device of the class described, a body portion of the desired shape and structure; air inlet and gas outlet holes for the passage of air and gas; a gas producing compound intermediate said inlet and outlet holes; and means to retard the

escape of gas from said compound to said outlet holes, said gas simulating smoke arising from said device.

2. In an illusionary device of the class described, a body portion of the desired shape and structure; inlet and outlet passages therethrough; a removable container within said body adapted to receive a quantity of gas producing material; a gas chamber in said container; and means to effect a retarded escape of gas from said container, said gas simulating smoke arising from said device.

3. In an illusionary device of the class described, a body portion of the desired shape and structure; air inlet and gas outlet holes therein; a removable container within said body portion; gas generating means in said container; and means within said body portion adapted to force a current of air through said container.

4. In an illusionary device of the class described, a body portion of the desired shape and structure; air inlet and gas outlet holes therein; a removable container; gas generating means in said container; a gas reservoir in said body portion; and means to retard the progress of gas to said reservoir, whereby the generated gas will slowly issue through said outlet holes and thus simulate smoke.

5. In an illusionary device of the class described, a body portion of the shape and structure desired; air inlet and gas outlet means in said body portion; a removable container in said body portion having gas generating means in one end thereof through which a current of air is adapted to be passed and a gas chamber in the other end thereof; means intermediate said generating means and said gas chamber to retard the passage of air through said generating means; and means in said gas chamber to effect the gradual escape of gas through said gas outlet means in said body portion, to thereby simulate smoke arising from said device.

6. In an illusionary device of the class described, a body portion of the desired shape and structure; air inlets and gas outlets in said body portion; a removable chamber within said body; two elements of highly volatile nature within said chamber separated from each other by a fibrous material; means to force a current of air through said elements and said fibrous material whereby the fumes given off by said elements will become mixed thereby generating a smoky gas; and a mass of fibrous material interposed between said elements and said gas outlet in said body portion through which said gas is forced to finally issue through said outlets to thereby simulate smoke arising from said device.

7. In an illusionary device of the class de-

scribed, a body portion having a chamber therein; an opening at one end of said chamber adapted to receive a container; a removable container in said chamber having communicating compartments therein; two elements of highly volatile nature in separate compartments and separated from each other by a compartment containing fibrous material both of said elements being separated from the said outlet holes in said body by another compartment containing fibrous material; and means to circulate a current of air through said chambers and said container whereby the fumes given off by the said elements will be concentrated and generate a gas resembling smoke or steam.

8. In an illusionary device of the class described, a body portion having a chamber therein; an opening in said body portion adapted to receive a container; communicating compartments in said container; inlet and outlet holes adjacent opposite ends of said body portion; outlet holes in said container so arranged as to register with said outlet holes in said body portion; means to generate gas in said container; and means to cause the holes in said container to register with said outlet holes in said body portion.

9. In an illusionary device of the class described, a body portion having a chamber therein; a removable container therein adapted to hold a charge of gas generating materials; inlet and outlet holes adjacent the ends of said body portion; holes in said container adapted to register with said outlet holes; guiding means on said container adapted to coact with guide ways in said body portion; and an agitator within said body portion adapted to force air through said chamber.

10. In a device of the class described, a cigar shaped body portion having a chamber therein; a removable container in said chamber; screen partitions in said container which separate said container into compartments; an agent capable of absorbing and retaining a quantity of hydrochloric acid in one of said compartments; a quantity of ammonium carbonate in another of said compartments; a quantity of fibrous material intermediate those two compartments; a quantity of fibrous material between said ammonium carbonate and another of said compartments; said chamber and divided container being so constructed and arranged that movement of said body portion through the atmosphere will force a current of air through said chamber and through and around said container whereby the mixture of air and the fumes of said acid and carbonate form a gas simulating smoke; and means to guide said container to its position within said chamber.

11. In an advertising device of the class

described, a cigar shaped body portion having a chamber therein; guide ways in said body portion; a container having holes therein adapted to register with holes in said body portion; gibs on said container adapted to coact with said guide ways; gas generating means in said container; and an electric fan in said chamber adapted to force a current of air through said chamber and

through and around said container, to thereby force the generated gas through said holes in said body portion to simulate smoke arising from said cigar shaped body portion. 10
